PHONOGRAPH RECORD ALBUM

Preston L. Andrews, Floral Park, N. Y.

Application February 26, 1947, Serial No. 731,111

2 Claims. (Cl. 129—20)

1

This invention relates to improvements in phonograph record albums; and the invention has reference, more particularly, to an album structure provided with novel means for mounting a plurality of phonograph record holding envelopes in hingedly retained relation to the back of the album and between the covers thereof.

The invention has for an object to provide in combination with the back and covers of an album, a novel construction of holding means for hingedly supporting the record receiving envelopes in connection therewith; said means comprising a rigid foundation member or back frame, which is adapted to form a part of the album back, and means, cooperative with said foundation member or back frame for engaging the envelopes, adapted, when the envelopes are operatively assembled therewith, to be received by and to be permanently affixed to said foundation member or back frame so as to become unitary therewith, and thus bind said envelopes into the album.

Another object of the invention is to provide a phonograph record album characterized as above set forth, which can be economically produced, with minimum expenditure of time and labor, and which provides an exceedingly strong and durable album structure.

Other objects of this invention, not at this time more particularly enumerated, will be understood from the following detailed description of the same.

An illustrative embodiment of the invention is shown in the accompanying drawings, in which:

Fig. 1 is a side elevational view of the foundation member or back frame and the record envelope attaching and hinging means disposed in initial disassembled relation; Fig. 2 is a top plan view of the foundation member or back frame per se; Fig. 3 is a longitudinal sectional view of the foundation member or back frame and the record envelope attaching and hinging means, with the latter operatively applied to the envelopes ready to be assembled with the former; Fig. 4 is a similar view, with said parts in operatively assembled relation; Fig. 5 is a horizontal sectional view, taken on line 5—5 in Fig. 4; Fig. 6 is a transverse sectional view, taken on line 6—6 in Fig. 4; and Fig. 7 is another transverse sectional view, taken on line 7—7 in Fig. 4.

Fig. 8 is a longitudinal sectional view through the complete album structure, said view being drawn on a somewhat reduced scale; and Fig. 9 is a fragmentary cross-sectional view, taken on line 55

line 9—9 in Fig. 8, but drawn on an enlarged scale.

Similar characters of reference are employed in the above described views, to indicate corresponding parts.

Referring to the drawings, the foundation member or back frame of the record holding envelope binding structure, according to this invention, comprises a body portion 10 of a length and width substantially corresponding to the desired length and width of the album back. Said foundation member or back frame is preferably of transversely convex shape, and is formed to provide inwardly offset, upstanding longitudinal ribs 11 along its inner face or side, so as to form laterally projecting, longitudinally extending marginal lip portions 12 along the outer sides of said foundation member or back frame. Said ribs 11 reinforce and contribute to the desired rigidity of the foundation member or back frame. At each end, said body portion 10 is provided with an upstanding, transverse end wall 13 of suitable thickness, the ends of which coincide with the outer faces of said ribs 11. Extending along the inner faces of said end walls 13 are inwardly offset shoulder portions 14 of reduced height, whereby their tops are downwardly offset from the top margins of said end walls 13. Said shoulder portions 14 are provided with upwardly open sockets 15, which are preferably coincident with the inner faces of end walls 13. Said foundation member or back frame, as thus constituted, may be made of any suitable material, but is preferably molded from a plastic material, whereby the parts thereof are integral so as to provide a rigid one-piece structure.

The record envelope attaching devices, as designed for operative assembled connection with the foundation member or back frame, each comprise a transverse bracket member 16, having at its rear or outer end a dependent anchoring tongue 17, which is sized to fit into a socket 15 of the foundation member or back frame. Extending forwardly or inwardly from the bracket member 16, in the horizontal plane thereof, are a plurality of laterally spaced fingers or prongs 18, which correspond in number to the number of record envelopes with which a given album is to be provided. Preferably, said prongs 18 are provided with tapered free end portions 19. Said attaching devices may also be made of any suitable material, but are preferably molded from a plastic material so that each comprises an integral of one-piece structure.

The phonograph record envelopes to be bound

into the album are, as is customary, fabricated from heavy sheet paper stock or like material to provide an outwardly open record receiving pocket. Each envelope is so constructed as to provide an endwise open hinging fold or loop portion 21 at the end or side thereof desired to be bound or anchored in the album structure.

To assemble the envelopes 20 for binding into the album, the required number thereof are grouped together, whereupon an attaching device is applied to each end of the group in such manner that each envelope is engaged by corresponding prongs 18 of the opposed bracket members 16 of said devices, whereby aligned opposed prongs 18 are respectively inserted into the opposite open ends of the hinging fold or loop portion 21 of each envelope. In this manner, not only are the envelopes 20 individually supported by opposed prongs 18 of the bracket members 16, but said envelopes are grouped in aligned and spaced in side by side relation according to the spacing of the prongs of said bracket members.

After the envelopes 20 and attaching devices have been assembled in the manner above described, the bracket members 16 of the latter are thereupon applied to and assembled with the foundation member or back frame. This is done by inserting the dependent anchoring tongues 17 of the bracket members respectively into the sockets 15 with which the shoulder portions 14, at the opposite ends of the foundation member or back frame, are provided. When thus assembled with the foundation member or back frame, the bracket members 16 of the attaching devices will be supported upon said shoulder portions 14 of the foundation member or back frame, and so that the envelope supporting prongs 18 will overhang the body portion 10 of the latter in upwardly spaced relation thereto. To permanently affix the attaching devices in the described assembled relation to the foundation member or back frame, the anchoring tongues 17 are coated with a suitable cement so as to firmly adhere to the walls of the sockets 15, whereby the assembly provides a strong and rugged unitary structure by which the envelopes engaged therewith are securely held against displacement.

The assembly of envelopes and supporting foundation having been completed, the same is ready to be bound into the covers of the album. The album cover may be variously made of any suitable materials. A preferred form of cover structure, as illustratively shown, comprises a sheet of selected binding material which provides cover portions 22 and an intermediate back portion 23. Said back portion 23 is disposed to overlie and is glued to the outer surface of the body portion 10 of the envelope supporting foundation, and so as to extend around the longitudinal lip portions 12 of the latter, whereby to form flexible hinging connections 24 along the tops of said lip portions, from which the cover portions 22 extend respectively over opposite sides of the envelope assembly. The cover portions 22 are preferably reinforced with binder's board 25, to and around marginal portions of which said cover portions are adhered, as by gluing the same thereto. To further anchor the cover structure to the envelope supporting foundation, and to reinforce the hinging connections 24 of said cover portions with the latter, internal strips of binder's cloth are provided, the outer end portions 26 of which are respectively glued to the inner faces of the binder's board 25 adjacent to the envelope sup-

porting foundation, so as to extend to and overlie the hinging connections 24 of the cover portions at 27, whereby to reinforce the latter; the inner end portions 28 of said strips extend thence over and around the ribs 11 of the body portion 10 of the envelope supporting foundation, and onto the inner face of said body portion, said inner end portions being firmly adhered to said ribs 11 and body portion 10 by gluing the same thereto. While the thus applied binder's cloth is shown as comprising two sections, it will be obvious that the same may be made and applied as a single strip extending from cover portion to cover portion over the body portion 10 of the envelope supporting foundation. The inner faces of the binder's board reinforced cover portions 22, and the outer end portions 26 of the strips of binder's cloth are each preferably overlaid with an applied internal facing or fly leaf 29, which is glued thereto, thus completing the album cover structure and its assembly with the envelope supporting foundation.

From the above description it will be understood that this invention provides a very strong, durable and easily assembled envelope supporting foundation for mounting a group of phonograph holding envelopes within a binding album structure, so that the envelopes will be firmly held in place and yet free to swing about the attaching prongs 18 of the supporting foundation when the album is opened and closed.

I am aware that some changes could be made in the above described constructions and without departing from the scope of this invention as defined in the herefollowing claims. It is therefore intended that all matter contained in the foregoing description or shown in the accompanying drawings shall be interpreted as illustrative and not in a limiting sense.

I claim:

1. In an album structure, means for binding a plurality of envelopes therein, each envelope having an endwise open hinging fold, said binding means comprising a rigid foundation member adapted to be secured to the back of the album structure, said foundation member having transverse upstanding portions at its respective ends provided with sockets facing perpendicular to the foundation member, a cooperating pair of bracket members having dependent anchoring tongues respectively entered and affixed in the respective sockets of the foundation member, whereby to join the bracket members to opposite ends of said foundation member, and said bracket members having a plurality of laterally spaced prongs extending inwardly therefrom parallel to the upper surface of the foundation member, corresponding prongs of the opposed bracket members being disposed in longitudinal alignment and entered in opposite ends of the respective envelope hinging folds, whereby to support said envelopes in attached relation to the foundation member.

2. In an album structure, means for binding a plurality of envelopes therein, each envelope having an endwise open hinging fold, said binding means comprising a rigid foundation member adapted to be secured to the back of the album structure, said foundation member having upstanding transverse end walls, shoulder portions contiguous to the inner faces of said end walls and of reduced height, said shoulder portions having upwardly open socket cavities therein, bracket members, said bracket members having dependent anchoring tongues respectively entered and affixed in said socket cavities, where-

by to support said bracket members on said shoulder portions respectively in joined relation to opposite ends of said foundation member, and said bracket members having a plurality of laterally spaced prongs inwardly extending therefrom above said foundation member, corresponding prongs of the opposed bracket members being disposed in longitudinal alignment and entered in opposite ends of the respective envelope hinging folds, whereby to support said envelopes in 10 attached relation to the foundation member.

PRESTON L. ANDREWS.
